CLAIM

The ornamental design for magazine for collecting film for a printer, substantially as shown and described.

DESCRIPTION

FIG. 1 is a front elevational view of a magazine for collecting film for a printer showing our new design; FIG. 2 is a rear elevational view thereof; FIG. 3 is a top plan view thereof; FIG. 4 is a bottom plan view thereof; FIG. 5 is a left side elevational view thereof; FIG. 6 is a right side elevational view thereof; FIG. 7 is a front perspective view thereof; and FIG. 8 is a front perspective view thereof with the cover open.

The shading on the stripes of FIGS. 1 and 7 is intended to show contrasting colors on the different stripes.

FIG. 1.**FIG. 2.**FIG. 3.

FIG. 4.

FIG. 5

FIG. 6
